DENTAL IMPRESSION DEVICE

William T. Shea, Buffalo, N. Y.

Application April 7, 1950, Serial No. 154,506

7 Claims. (Cl. 32—19)

1

This invention relates to apparatus for use in the science of dentistry and particularly in the practice of prosthetics.

In preparing dentures and particularly in the preparation of more or less complete dentures, the practice is to make an impression of the interior of the patient's mouth, particularly of the alveolar ridge, or of both alveolar ridges in the cases where both upper and lower dentures are to be made and fitted. From these impressions models are made for use by the prosthodontist or manufacturing dentist. These models are replicas of the upper and lower alveolar ridges of the patient after all contemplated tooth extractions have been made.

From these models the prosthodontist or manufacturing dentist makes what is known as a base plate tray, and upon this base plate tray he builds up a U-shaped wall of wax or the like known as a bite block and proportioned to approximately define the outlines of the teeth to be built up on the ultimate plate or denture. This wax bite block is not a representation of the individual teeth, but merely a solid wall defining the space which the teeth will occupy. The bite block portion may be of wax or may comprise a shellac base with a wax bite portion.

These bite blocks are then inserted in the mouth of the patient to determine the required depth of the teeth to be built up on the projected denture and to determine the correct vertical alignment or registry of upper and lower plates, the latter characteristic being known in this art as the determination of correct centric.

When proper adjustments have been made and the patient finally bites down and both bite blocks are in correct relative position and the correct depth of bite has been determined, the dentist seals the sides of the upper and lower bite blocks to each other by applying a hot spatula to the wax at one or more points along the line where the bite blocks meet. The bite blocks are then removed from the patient's mouth, and the manufacture of the dentures is proceeded with in conventional ways, using the bite blocks to determine proper depth and registration or centric so that the ultimate teeth occlude properly.

It is known in the art that correct registration or centric of upper and lower bite blocks is difficult to attain, because patients have a tendency to distort their lower jaw laterally in bearing down upon the bite blocks, so that a false centric may result. It is also known in the art that the lower jaw may be readily immobilized if the

2

tongue of the patient is pushed backward in the oral cavity and held in such position. The actual accomplishment of this result in this manner has heretofore been considered impractical because the interior of the patient's mouth is inaccessible when the bite blocks are closed or brought together, and the degree of movement of any individual patient's tongue to secure immobilization varies widely.

10 The present invention provides a simple device which may be incorporated in one of the bite blocks, more conveniently the lower bite block, at the time the bite blocks are made, for use by the dentist in readily pushing back the tongue to just the proper degree and holding it so pushed back when the bite blocks are closed and ultimately sealed to each other. While a single form of the device of the present invention is illustrated in the drawing and described in the following specification, it is to be understood that that form is by way of example only, and that many mechanical modifications may be made without departing from the spirit of the invention, which is limited only as defined in the appended claims.

In the drawing:

Fig. 1 is a schematic representation of a portion of a human head, particularly the mouth portion and the alveolar ridges, showing a pair of bite blocks in position and one form of the device of the present invention associated therewith;

Fig. 2 is a top plan view of the lower bite block of Fig. 1; and

Fig. 3 is a fragmentary cross-sectional view on the line 3—3 of Fig. 2.

In the several figures of the drawing, like characters of reference denote like parts, and the numerals 10 and 11 designate schematically the upper and lower alveolar ridges of a patient. Upper and lower base plate trays are designated 12 and 13, and the bite blocks carried thereby are designated 14 and 15, respectively.

45 The device of the present invention, in the form illustrated in the drawing, comprises a generally cylindrical sleeve-like holder designated generally 16 and comprising an externally flattened portion 18 at one end and a tapered split threaded portion 19 at the other end. The flattened portion 18 is adapted to be embedded in lower bite block 15 at its front central portion when the latter is cast or molded, the sleeve 16 extending longitudinally with its split threaded portion outwardly of the front surface of bite

block 15. The flats of portion 18 prevent inadvertent rotation of sleeve 16 in the bite block.

A rod element 21 is preferably provided with a head formation 22 at its outer end and is threaded at its inner end as at 23 to screw into a hub portion 24 of an arcuate pushing plate 25.

After sleeve 16 is cast in position in bite block 15, rod 21 is inserted in sleeve 16 and the arcuate pushing plate 25 is threaded onto the inner end 23 of rod 21. A knurled thumb nut 27 may be employed in conjunction with the split threaded portion 19 of sleeve 16, either to lock the rod 21 in a desired position of adjustment or to cause just enough friction between rod 21 and the interior of sleeve 16, so that rod 21 will remain frictionally in any desired position of axial adjustment but may be manipulated axially in sleeve 16 when desired.

In using the device of the present invention, after it has been fully assembled with the bite block as described above, the dentist may either apply pressure to head 22 of rod 21 to hold the patient's tongue in the approximate position indicated at 30 in Fig. 1, or he may push the tongue to such position by pressure upon head 22 and then lock the pusher with respect to sleeve 16 by tightening nut 27. In either case the tongue is held back to whatever degree is necessary to immobilize the lower jaw of the patient, particularly with respect to lateral distortion, so that correct registration of the upper and lower jaws is assured, and, accordingly, correct centric of the bite blocks is readily attained.

What is claimed is:

1. Means for use in dental bite blocks comprising a sleeve adapted to be anchored in the front central portion of a bite block with its axis generally horizontal and perpendicular to the front surface of the bite block, a rod slidable in said sleeve and having a manipulating portion adapted to extend outside of the bite block and a generally vertical tongue pushing plate at the end of said rod adapted to be positioned interiorly of the bite block, and means for yieldably retaining the rod in axially adjusted position in said sleeve.

2. Means for use in dental bite blocks comprising a sleeve adapted to be anchored in the front central portion of a bite block with its axis generally horizontal and perpendicular to the front surface of the bite block, a rod slidable in said sleeve and having a manipulating portion adapted to extend outside of the bite block and a generally vertical tongue pushing plate at the end of said rod adapted to be positioned interiorly of the bite block, and adjustable means on said sleeve for causing the rod to be frictionally retained in axially adjusted position in said sleeve.

3. Means for use in dental bite blocks comprising a sleeve adapted to be anchored in the front central portion of a bite block with its axis generally horizontal and perpendicular to the front

surface of the bite block, a rod slidable in said sleeve and having a manipulating portion adapted to extend outside of the bite block and a generally vertical tongue pushing plate at the end of said rod adapted to be positioned interiorly of the bite block, and means for selectively retaining the rod in axially adjusted position in said sleeve.

4. Means for use in dental bite blocks comprising a sleeve having a non-circular exterior surface for anchoring the sleeve in the front central portion of a bite block with its opposite ends exposed at the front and rear surfaces of the bite block, a rod slidable in said sleeve when said sleeve is anchored in a bite block and having a manipulating portion adapted to extend outside of the bite block and a tongue pushing plate at the end of said rod adapted to be positioned interiorly of the bite block.

5. Means for use in dental bite blocks comprising a sleeve adapted to be anchored in the front central portion of a bite block with its axis generally horizontal and perpendicular to the front surface of the bite block, a rod slidable in said sleeve and having a head portion at the end adapted to be positioned outside of the bite block and a generally vertical tongue pushing plate at the end adapted to be positioned inside of the bite block, and means for retaining the rod in axially adjusted position in said sleeve.

6. Means for use in dental bite blocks comprising a sleeve adapted to be anchored in the front central portion of a bite block with the openings at its opposite ends exposed at the front and rear surfaces of the bite block, a rod slidable in said sleeve when said sleeve is anchored in a bite block and having a manipulating portion adapted to extend outside of the bite block and a tongue pushing plate at the end adapted to be positioned inside of the bite block.

7. Means for use in dental bite blocks comprising a sleeve adapted to be anchored in the front central portion of a bite block with its axis generally horizontal and perpendicular to the front surface of the bite block, a rod slidable in said sleeve when said sleeve is anchored in a bite block and having a manipulating portion adapted to project outside of the bite block and a generally vertical tongue pushing plate at the end adapted to be positioned inside of the bite block, the face of said plate which is directed toward the rear of the mouth being convex in at least one direction.
